UNITED STATES PATENT OFFICE.

CHARLES B. PENDLETON, OF DENVER, COLORADO.

AUTOMATIC FLUID-PRESSURE DISPLACEMENT PUMP.

Application filed April 12, 1921. Serial No. 460,742.

To all whom it may concern:

Be it known that I, CHARLES B. PENDLETON, a citizen of the United States, residing at the city and county of Denver and State 5 of Colorado, have invented certain new and useful Improvements in Automatic Fluid-Pressure Displacement Pumps; and I do hereby declare the following to be a full, clear, and exact description of the invention, 10 such as will enable others skilled in the art to which it appertains to make and use the same.

This invention relates to improvements in fluid pressure liquid displacement pumps.

Under certain conditions at least, and with or without minor alterations or adaptations, the improvements may well be employed broadly in analogous relations other than for pumping water, and for that reason the invention is not necessarily restricted to any limited field of use, still the particular improvements involved have been more especially devised with reference to use with large volumes of water to be pumped, 20 under varying conditions and for varying purposes, and the invention will be described, therefore, with particular relation to the pumping of water only.

For a clearer conception at the outset of the numerous advantages of the improvements and the varied spheres or ranges of utility, it may not be amiss to first briefly enumerate some of such purposes and usages, as follows:

The pumping from rivers, streams, lakes, deep wells, or equivalent bodies of water, for irrigation projects, aims or purposes; the pumping out of mines, pools or water filled and flooded areas generally, for reclamation purposes; the pumping to substantially higher levels for supplying lakes, reservoirs, canals, ditches or for other analogous purposes, in substitution for hydraulic rams or the like, and in fact wherever large quantities of water are required; and the maintaining of the requisite pressure throughout any system of water piping, wherein there is provided an air release valve in the discharge line, so that the drawing of water is immediately available at any regulable outlet in the line, owing to the constant pressure maintained throughout the same. In the latter instance, therefore, fresh water

may be obtained from the bottom of a well at all times, obviating the necessity of an elevated tank or tower customarily employed for supplying such pipe line pressures, and incidentally eliminating the objectionable feature of freezing up in winter, while in the summer permitting of always drawing cool water from the bottom of a well instead of having to use warm or standing water. Furthermore, a simple installation may be associated with any well, making it feasible for suburbanites, or others in outlying or sparsely settled districts, and more especially farmers and ranchers to always have water readily accessible, under pressure, for supplying the home, barn, corrals, pens and other places locally.

In an earlier patent of mine, No. 1368528 of February 15, 1921, the invention was primarily devised for the pumping of oil wells, and embodies a liquid controlling foot valve cooperating with an operating fluid pressure controlling head valve, the control of which valvular elements as well as the actuation thereof being both fully automatic, inasmuch as the operating pressure line is designed to be generally open to its source of supply, so that the pumping operations start up of their own accord just as soon as the oil in the well casing has risen to or above a certain level, and continuous pumping will only cease when the oil level falls below that position.

In the instant application there is employed a unitary valvular element which controls both the supply of operating pressure fluid to the pump proper as well as the water supply thereto, regardless of the water level which is always sufficiently high, and to this extent the pump is likewise fully automatic when the operating pressure line is open to its source of supply. In another sense, however, in comparison with my aforesaid patent, it may be said to be only semi-automatic, inasmuch as the operating pressure line is not designed to be generally open to its source of supply, but is only opened thereto when it is desired to start pumping operations and is shut off therefrom when the pumping is to be stopped. Hence the actual control is not wholly automatic as in my patent aforesaid, the necessities in oil pumping being under most con-

ditions quite different from water pumping, because in the case of oil wells the level of oil in the well casing periodically falls so low that there is no real production until the lower end of the casing substantially fills up again.

With these prefacing remarks, and as other objects and advantages of the invention as well as those already enumerated 10 will be fully apparent as incidental to the following disclosure, reference will now be immediately had to the accompanying drawings, illustrating certain practical embodiments of the improvements, in which 15 drawings—

Figure 1 is a vertical sectional view through an extraordinarily large displacement chamber, with one arrangement of my pumping equipment projected upwardly 20 therein, which is especially designed for pumping from lakes, streams or the like, the displacement chamber being of substantially greater length than height, and the casing wall thereof being broken away for convenience of illustration; Figure 2 is a view substantially analogous to Figure 1, but illustrating a displacement chamber of greater height than width, requiring a substantial elongation of the pumping parts; Figure 25 3 is a view somewhat analogous to Figure 2, but with the valvular elements mounted from the top of the displacement chamber, and reducing the length of some of the parts; Figure 4 is a view substantially 30 analogous to Figure 2, but with a cup-shaped water control valve end and suitable casing therefor; and Figure 5 is a vertical sectional view of a still further modified arrangement particularly designed for certain 35 uses, when only a very small displacement chamber is required, as with very deep wells in which the water level stands up to an extremely high position, say approximately a hundred feet of more.

40 As the broader features embodied in all of the illustrations involve substantially the same identical principles, and for brevity of description, the analogous parts in all of the views of the drawings will be indicated as 45 far as possible by the same reference characters.

In this connection, the numeral 10 designates either the displacement chamber or the casing wall thereof, providing a water 50 inlet 11, shown at the bottom thereof, and a water discharge pipe or outlet conduit 12, in communication with the lower portion 55 of the displacement chamber and extending upwardly therefrom to its discharge position.

60 Within the displacement chamber 10 there is suitably mounted a valve casing 13 for housing the operating pressure fluid control valvular member 14, the latter providing a 65 peripheral portway 15 that cooperates with

a pair of operating pressure line ports 16-17, in all instances, and with relief ports 18-19 in all instances excepting in Figure 5. These ports 16-17-18-19 are disposed in complementary pairs, and preferably provide a threaded form of openings extending through the peripheral wall of the valve casing 13.

70 20 indicates the inlet section of an operating pressure fluid line that extends upwardly 75 to a suitable source of pressure fluid supply, such as compressed air, and the flow from said source of supply to said inlet section being under suitable valvular control, not illustrated, while 21 is the outlet section of 80 said operating pressure fluid line, the discharge end of said outlet section being in communication with said displacement chamber 10 towards the upper end thereof.

85 The exit end of the section 20 communicates with the port opening 16 and the entrant end of the section 21 communicates with the port opening 17, which is oppositely disposed diametrically of the port opening 16, so that there is a gap or interrupted zone 90 in the operating pressure fluid line through the casing 13.

95 22 indicates the inlet section of a pressure relief or air releasing conduit, the entrant end of which is in communication with the displacement chamber 10, towards the upper portion thereof, and the exit end of which is in communication with the port opening 18, while 23 is an outlet section 100 thereof, providing a communicating conduit between the port opening 19 and the water discharge pipe 12. Analogously to the operating pressure fluid conduit, the relief conduit also has a gap or interrupted zone 105 through the valve casing chamber 13.

110 In all instances the lower end of the valvular member 14 terminates in a water inlet control valvular member indicated by the numeral 24, in Figures 1 to 3, as an ordinary flat seating element carried by a 115 stem 25 depending from the valvular member 14, while at Figure 4 the water inlet control valve is indicated at 26 as an elongated inverted cylindrical cup element, and at Figure 5 as a closed cylindrical element 27.

120 The arrangement of Figure 1 is primarily intended for use where the water is to be pumped from a lake, stream or the like, in large volumes or charges, and in this case 125 the displacement chamber may well be of substantially greater dimensions horizontally than the depth thereof, the casing being adapted to be entirely submerged, and supported substantially above the bed of the body of water. Although not shown, it is obvious that a suitable screen or grating may be associated with the inlet 11 to prevent fish, débris or other substantial foreign matter from entering the displacement chamber 130

ber. Such a screening medium may likewise be associated with the water inlet of any of the other structures, which latter however are more particularly intended to be lowered 5 into wells.

In both Figures 1 and 2, it will be noted that the valve casing 13 is projected upwardly from the bottom of the displacement chamber, and the only real substantial difference between these two structures is that in the structure of Figure 2 the displacement chamber is elongated vertically instead of horizontally. This will necessitate the elongation of its conduit sections 21-22 also, so 10 that their open ends will terminate towards the top of the chamber.

Also in Figure 1 the valve seat 28, embodying the water inlet 11, is shown as being threaded into the bottom of the displacement chamber, and provides a spider element or open cage-work 29 at the inner side of the valve seat, whereas in Figure 2 the valve seat 30 is shown as integrally formed with the bottom, although it may be as in Figure 1, and the spider support 31 is shown as of slightly different form but analogous to the open cage-work 29. None of these details, however, are particularly germane to the essential invention.

In Figure 3 the displacement chamber is vertically elongated as in Figure 2, but the valve casing 13 is suspended from the top of the displacement chamber, thus permitting of the shortening of the conduit sections 21-22, although requiring the elongation of the depending stem 25. There are other minor details of mounting, indicated generally at 32, but all of these little features will clearly appear from the drawings without further description.

In Figure 4, the arrangement is again substantially the same as in Figure 2 in point of dimensions, and somewhat like Figure 1 in the mounting of the water valve seat supporting the pressure control valve casing, 33 indicating the water valve seat providing an annular seating recess 34, and 35 indicating ports or openings, equivalent to the open cage-work before referred to. In this figure, however, the lower portion of the valve casing 13 is substantially enlarged to provide a dash-pot-like chamber 36 for receiving the cup-shaped water valvular element 26, and 37 indicates relief vents or 55 apertures for the chamber 36 upon the upward stroke of the valve 26.

The structure in Figure 5 is somewhat analogous to Figure 4, although this modified arrangement is especially designed for wells where only a small displacement chamber is required, as hereinbefore referred to, and the length and cross-sectional dimensions of the displacement chamber may therefore be greatly reduced. In fact, the 65 diameter of the casing 10 is just sufficiently

greater than that of the discharge pipe 12 (the diameter of which latter may be substantially increased) to fully encompass all of the parts. In this construction, the operating pressure line section 20 is contained 70 within the discharge pipe 12, and the relief conduit 22-23, together with the associated port openings 18-19, may be entirely dispensed with.

There is a reduced portion or shank 38 75 connecting the valvular elements 14 and 27, and an annular space 39 is formed to receive the projecting end of a stop screw element or abutment 40.

In Figure 5 the unitary valvular parts 80 are shown elevated, and the upstroke of the same is limited by the stop abutment 40 being engaged by the shoulder 41. The descent of the unitary valvular parts is analogously limited by the stop abutment 40 85 being engaged by the shoulder 42. In Figure 4, the upstroke is limited by the shoulder 43 of the cup valve 26 engaging the shoulder 44 of its casing, while the descent is limited by the lower edge face of the cup shaped 90 valve seating on the annular ledge 34. In Figure 3, the upstroke is limited by the valve member 14 engaging the plug 32, and the descent in this structure, as well as of Figures 1 and 2, is limited by the water control 95 valve 24 striking its seat. The limitations of the upstroke in Figures 1 and 2 will likewise be apparent.

In all of the illustrations, at the end of the valvular descent, the operating pressure 100 fluid line 20-21 is maintained open by the peripheral portway 15 coming into registration with the port openings 16-17, while in Figures 1 to 4, at the end of the valvular upstroke, the relief line 22-23 is maintained 105 open by the registration of the peripheral portway 15 with the port openings 18-19, and all of which features will be more clearly apparent after describing the pulsating operations of the unitary combined 110 valvular parts, which operations will now be set forth.

The same description of operations will in substance apply to all of the figures, excepting with reference to the omitted parts 115 of Figure 5. Referring briefly to Figure 1, therefore, and assuming that the displacement chamber will have been filled with water and that the water inlet control valve has in consequence become seated by gravitation, owing to the equalization of pressures within and without the displacement chamber 10, then the descent of the air control valve 14 will have brought the portway 15 into registration with the port openings 125 16-17. The parts being in this position, therefore, it follows that the compressed air line is now open and, providing the inlet section 20 is open to its source of supply, the operating pressure fluid will flow down 130

the section 20 and up the section 21, discharging from the latter above the volume of water in the displacement chamber, and functioning as a fluid piston head will force 5 the water down towards the bottom of the displacement chamber and up the discharge pipe 12.

When the charge of water has been substantially exhausted, the head of air will 10 start to escape initially up the discharge pipe 12 through its bottom opening, and this initial relief will cause the pressure within the displacement chamber to become less than the water pressure outside, where- 15 upon the valvular parts will be automatically elevated by the water from the outside rushing in through the inlet 11 to fill the displacement chamber again. As the valvular parts start to rise, the registration be- 20 tween the portway 15 and the port openings 16-17 is closed and the pressure fluid line cut off, but registration between the portway 15 and the port openings 18-19 is estab- 25 lished to open the relief line, so that the head of air above the incoming water es- capes down the section 22 and up the sec- 30 tion 23, escaping into the water discharge pipe 12. The pipe 12 may have a check valve (not shown) disposed above the en- 35 trance of the relief section 23, to prevent the column of water thereabove from descend- 40 ing below the same.

When the displacement chamber has been again refilled, the same cycle of operations 35 will be repeated, and it is obvious that these automatic pulsating actuations will continue indefinitely, as long as the pressure line section 20 is in open communication with its source of supply maintained under suffi- 40 ciently high pressure, and as long as the exit end of the discharge pipe 12 is not closed. By a suitable valvular control of the latter, however, such as faucets in re- 45 duced branch lines, pumping could be con- trolled from the discharge outlet pipe, mak- 50 ing the invention applicable for use in any pressure line system, as hereinbefore re- ferred to.

When associated with a well wherein the 50 water column stands up very high, the need of a large displacement chamber becomes less essential, and, for straight pipe connec- 55 tions, the comparatively smaller dimensioned structure of Figure 5 would doubt- less be found fully satisfactory, it being noted that in this arrangement the volume of the displacement chamber strictly speak- 60 ing, or the portion thereof so functioning, would in reality only embody that area dis- posed between the top of the casing 10 and the bottom of the pipe 12, which latter in this particular case extends but a very short distance within the top portion of the cham- 65 ber 10. In view of the comparatively minor volume of the fluid piston head established

with this construction, it will be obvious that there is no essential need for employing an air relief conduit, as has been illustrated in connection with Figures 1 to 4.

From the foregoing replete description, it is believed that the full advantages of my improvements will be clearly apparent, and while I have thus disclosed certain preferred embodiments of my invention, it may be later found to be expedient or desirable 75 to make some alterations in the structural form and arrangement of the parts, but without departing from the spirit of the invention. It will be understood, therefore, that I do not necessarily restrict myself to 80 all of the details exactly as disclosed, excepting as they may come within the terms of the ensuing claims, or as when fairly interpreted in the light of the specification if necessary. 85

What I do claim, as new and patentable, is:—

1. In pumps of the character disclosed, embodying a displacement chamber providing a liquid inlet and adapted for submer- 90 sion in a volume of the liquid to be pumped, the combination of a liquid control valve for said inlet operating to its open position by the exterior liquid pressure thereon and re- 95 versely by gravitation upon the liquid filling of said chamber, a liquid discharge conduit leading from said chamber, a valve casing in said chamber and pro- 100 viding complementary ports, an inlet and an outlet conduit section, for an operating pressure fluid, in complementary com- 105 munication with said ports, the last said conduit section opening to the upper portion of said chamber, and a pressure control valve providing a portway registering with 110 said ports when said liquid control valve is closed, the said pressure control valve being so connected with said liquid control valve that the former is actuated by the latter.

2. In pumps of the character disclosed, embodying a displacement chamber providing a liquid inlet and adapted for submer- 115 sion in a volume of the liquid to be pumped, the combination of a valve casing in said chamber and providing complementary ports, an inlet and an outlet conduit section, for an operating pressure fluid, in complementary communication with said ports, the last said conduit section opening to the 120 upper portion of said chamber, a liquid dis- charge conduit leading from said chamber, a liquid control valve for said inlet disposed in line with said valve casing, operating to its open position by the exterior liquid pres- 125 sure thereon and being reversely operated by gravitation upon the liquid filling of said chamber, and a pressure control valve, housed by said valve casing, providing a portway which registers with said ports 130 when said liquid control valve is closed, the

said pressure control valve being so connected with said liquid control valve that the former is coincidently actuated by the latter.

5. 3. In pumps of the character disclosed, embodying a displacement chamber providing a liquid inlet and adapted for submer-
10 sion in a volume of the liquid to be pumped, the combination of a liquid control valve for said inlet, operating to its open position by the exterior liquid pressure thereon and re-
15 versely operating by gravitation upon the liquid filling of said chamber, a liquid dis-
charge conduit leading from said chamber,
20 a valve casing in said chamber and providing an upper and a lower set of complemen-
tary ports, an inlet and an outlet conduit section, for an operating pressure fluid, in
25 complementary communication with one set of said ports, the last said conduit section opening to the upper portion of said chamber, an inlet and an outlet conduit section, for relieving the air pressure in said chamber, in complementary communication with
30 the other said set of ports, said relief inlet section opening to the upper portion of said chamber and said relief outlet section com-
municating with said discharge conduit, and a pressure control valve providing a port-
35 way alternately registering with said sets of ports, the said pressure control valve being so connected with said liquid control valve that the former is actuated by the latter.

4. In pumps of the character disclosed, embodying a displacement chamber providing a liquid inlet and adapted for submer-
10 sion in a volume of the liquid to be pumped, the combination of a liquid discharge conduit leading from said chamber, a valve casing in said chamber and providing an upper and a lower set of complementary ports, an inlet and an outlet conduit section, for an operating pressure fluid, in complementary communication with one set of said ports, the last said conduit section opening to the upper portion of said chamber, an inlet and an outlet conduit section, for relieving the air pressure in said chamber, in complementary communication with the other said set of ports, said relief inlet section opening to the upper portion of said chamber and said relief outlet section communicating with said discharge conduit, a liquid control

valve for said inlet disposed in line with said valve casing, operating to its open po-
55 sition by the exterior liquid pressure thereon and being reversely operated by gravita-
60 tion upon the liquid filling of said chamber, and a pressure control valve, housed by said valve casing, providing a portway which al-
ternately registers with said sets of ports, the said pressure control valve being so con-
65 nected with said liquid control valve that the former is coincidently actuated by the latter.

5. In pumps of the character disclosed, embodying a displacement chamber providing a liquid inlet and adapted for submer-
70 sion in a volume of the liquid to be pumped, the combination of a liquid discharge con-
duit leading from said chamber, an operat-
75 ing pressure fluid line discharging to the upper portion of said chamber, and a pres-
sure control valve disposed in said pressure fluid line within said chamber, which pres-
80 sure control valve also provides a liquid inlet control valve associated with said liquid inlet, the whole said valvular structure be-
ing actuated in one direction by the exterior liquid pressure thereon and being actuated in the reverse direction by gravitation upon the liquid filling of said chamber.

6. In pumps of the character disclosed, embodying a displacement chamber providing a liquid inlet and adapted for submer-
85 sion in a volume of the liquid to be pumped, the combination of a liquid discharge con-
duit leading from said chamber, an operat-
90 ing pressure fluid line discharging to the upper portion of said chamber, an air re-
lief line open to the upper portion of said chamber and communicating with said li-
95 quid discharge conduit, and a combined pres-
sure control and air relief control valve, dis-
posed in said pressure fluid and air relief lines within said chamber, which valve also
provides a liquid inlet control valve associ-
100 ated with said liquid inlet, the whole said valvular structure being actuated in one di-
rection by the exterior liquid pressure there-
on and being actuated in the reverse direc-
tion by gravitation upon the liquid filling of said chamber.

In testimony whereof, I affix my signature.

CHARLES B. PENDLETON.
